[57] CLAIM

The ornamental design for an accessory tray for medicine cabinet, as shown and described.

DESCRIPTION

FIG. 1 is a perspective view of an accessory tray for medicine cabinet showing our new design the broken-line disclosure of a medicine cabinet being for illustrative purposes only and forming no part of the claimed design;

FIG. 2 is a front elevational view thereof;

FIG. 3 is a top plan view thereof; and,

FIG. 4 is an end view thereof, the opposite end being a mirror image of the end shown.
